UNITED STATES PATENT OFFICE

HARRY J. BRINKMAN, OF DAYTON, OHIO

SPRING CUE FOR TOY USE

Application filed June 20, 1927. Serial No. 199,947.

My invention relates to spring actuated cues for playing pool and billiards, crokinole or carom games and the like. While the 5 spring cue forming the subject matter hereof has been particularly designed for use with toy or miniature pool and billiard tables and for use on crokinole boards, the construction in larger forms and proportions is capable of general use for game purposes.

10 It is recognized that spring actuated cues have heretofore been manufactured and that a number of patents have already been issued therefor. However the present invention pertains to particular features of construction 15 which enable and facilitate the commercial production of spring cues at nominal cost and without the necessity of employment of highly skilled workmen.

In the present construction there is employed a reciprocating cue stick upon which is slidably mounted a sleeve formed from sheet metal by rolling or forming a strip of sheet metal stock into tubular form by bringing the opposite longitudinal margins into 25 proximity to each other. The sleeve is provided at spaced intervals, preferably at a medial point, and adjacent to each end with an integral peripheral bead formed in such sheet metal tube. The sleeve, being of greater diameter than the cue stick, is provided with heads closing the opposite ends of the sleeve into substantial conformity with the periphery of the cue stick. These heads are formed by inturned 30 tongues of material formed integral with the sleeve. The tongues at one end are offset and extended to form a short neck conforming to the cue stick. Within the reciprocating sleeve and surrounding the cue stick is a helical spring, one end of which abuts upon the 35 sleeve and the other end of which abuts upon a collar fixedly secured upon the cue stick within the sleeve. For economy of manufacture this collar comprises a split ring of round wire contracted tightly about the cue stick so as to become partially embedded therein.

The object of the invention is to simplify the structure as well as the mode of assembly of such spring actuated cues whereby they 50 will not only be cheapened in construction

but will be more efficient in use, positive and uniform in action, easily operated and unlikely to get out of repair.

A further object of the invention is to provide an improved form of a reciprocating sleeve for spring actuated cue sticks made from sheet metal and formed with integral closure heads. 55

A further and important feature of the invention is to provide an improved form of abutment collar for an actuating spring and to improve the method of attaching such abutment collar by contracting it tightly upon the cue stick. 60

With the above primary and other incidental objects in view as will more fully appear in the specification, the invention consists of the features of construction, the parts and combinations thereof, and the mode of operation, or their equivalents, as hereinafter described and set forth in the claims. 65

In the accompanying drawing wherein is shown the preferred, but obviously not necessarily, the only form of embodiment of the invention, Fig. 1 is a perspective view of the assembled spring actuated cue forming the subject matter hereof. Fig. 2 is a longitudinal sectional view illustrating the assembly of the spring and sliding sleeve upon the cue stick. Figs. 3 and 4 are end views from opposite ends of the assembled cue stick. Fig. 5 is a detail view of the contractible abutment collar prior to its application to the cue stick. Fig. 6 is a perspective view showing the abutment collar contracted upon the cue 75 stick. Fig. 7 is an enlarged detail sectional view illustrating the embedment of the abutment collar in the material of the stick. 80

Like parts are indicated by similar characters of reference throughout the several 90 views.

Referring to the accompanying drawings 1 is the cue stick which may be of any suitable or desired length and diameter. Slidably mounted upon the cue stick 1 is a tubular 95 sleeve 2 of somewhat greater diameter, preferably formed from sheet metal. The metal sleeve 2 is provided at a medial point and also adjacent to each end with peripheral beads 3 formed in the material of the sleeve. 100

These peripheral beads 3 afford finger grips and enable the sleeve to be held tightly without slipping. At each end of the sleeve there are preferably formed tongue like extensions which are inturned to form closure heads. The tongues 4 which are of an approximate sector shape are bent inwardly toward the cue stick and thence extended substantially parallel therewith to form a short bearing neck 5 substantially conforming to the periphery of the cue stick but within which the stick is quite free to move longitudinally. It is obvious that the ends of the sleeve might be upset or contracted in a forming die without the necessity of providing the sector-shaped tongues 4. However, the formation of such tongues 4 greatly facilitates and cheapens the manufacturing operation and assembly. These tongues are preferably in-turned and shaped to the required form in a suitable die. The formation of the sector-shaped tongues however, enables the use of cheap material and facilitates the forming operation, the construction being much less expensive than when the ends of the tube are closed by being contracted or formed without the removal of the gores of material intermediate the sector shaped tongues. The opposite end of the sleeve 2 is similarly provided with sector-shaped tongues 6. These tongues 6 are also inbent into substantial conformity with the periphery of the cue stick, without however, being extended to form a neck or hub. It is obvious however, that both ends of the reciprocatory sleeve 2 may be provided with like heads: that is to say, both ends of the sleeve may be formed with the extended neck 5 as shown in Figs. 1 and 3, or both ends of the sleeve may be devoid of such extension as shown in Fig. 4, and at the right in Fig. 2. Surrounding the cue stick 1 within the sleeve 2 is a helical actuating spring 7. The spring bears at one end (the left hand end in Fig. 2) against the inturned extremity or head of the sleeve 2. At its opposite end the spring 7 bears upon a peripheral collar 8 carried by the cue stick 1. It has been the practice heretofore to provide a transverse pin in the cue stick for the abutment of the spring in lieu of the collar 8, or to provide a thin collar of sheet metal secured to the cue stick by staking. For economy of manufacture and facility of assembly the abutment collar 8 in the present instance comprises a split ring, preferably though not necessarily, formed from round wire. This wire split ring being placed about the cue stick at the proper point is contracted tightly thereon. This contraction may be effected by rolling or by a setting die or may be effected by a pair of pincers or pliers with which the split ring is grasped and squeezed. The contraction of the ring upon the cue stick 1 partially embeds the inner circumference of the ring in the surface of the cue stick indenting the

stick as indicated at 9 in Fig. 7. By this means the abutment collar is immovably secured upon the stick quickly and easily by an inexpensive operation.

It will be understood that the collar 8 is applied to the cue stick and the spring is positioned thereon and such cue stick carrying the spring and collar is inserted in the reciprocatory sleeve 2 before one of the ends or head of the sleeve 2 is inturned. 75

The abutment ring 8 may be formed from square wire, or flat strips, or may be formed from special rolled wire shapes.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages. 80 85

While in order to comply with the statute the invention has been described in language more or less specific as to structural features, 90 it is to be understood that the invention is not limited to the specific details shown, but that the means and construction herein disclosed comprises the preferred form of several modes of putting the invention into effect, 95 and the invention is therefore claimed in any of its forms or modifications within the legitimate and valid scope of the appended claims.

Having thus described my invention, I 100 claim:

1. The combination with a spring actuated cue stick and actuating spring therefor, of a reciprocatory sleeve mounted on the stick and enclosing the spring, said sleeve being formed from sheet metal, a series of terminal tongues formed at one end of the sleeve, said tongues being offset inwardly to form an internal annular shoulder and a tubular projection of less diameter than the main body of the sleeve projecting beyond the shoulder. 105

2. The combination with a spring actuated cue stick and actuating spring therefor, of a reciprocatory sleeve mounted on the stick and enclosing the spring; said sleeve being formed from sheet metal, a series of terminal tongues formed at one end of the sleeve, said tongues being inturned to closure head for the sleeve substantially conforming to the periphery of the cue stick. 115

3. The combination with a spring actuated cue stick and an actuating spring therefor, of a reciprocatory sleeve mounted thereon and enclosing the spring, comprising a single sheet of material bent to tubular form with the longitudinal opposite edges of the sheet turned to proximate relation with each other, and the opposite ends of the tube thus formed contracted into proximate relation with the periphery of the cue stick. 125

4. The combination with a spring actuated

cue stick and actuating spring therefor of a reciprocalty sleeve surrounding the cue stick and spring, and a plurality of terminal integral tongues formed on opposite ends of said sleeve contractable into proximate relation with the periphery of the cue stick to prevent the escape of the spring and stick from the sleeve.

In testimony whereof, I have hereunto set
10 my hand this 21st day of May, A. D. 1927.

HARRY J. BRINKMAN.
